UNITED STATES PATENT OFFICE

RICHARD J. WILLIAMS, OF VIRGINIA, MINNESOTA

SAFETY HANDLE FOR AIR HOISTS

Application filed June 25, 1927. Serial No. 201,303.

The invention pertains to a safety lock for a throttle lever and more particularly to a safety handle lock applied to the throttle of an air hoist or winch.

In the service operation of a winch or hoist, a rope is applied to the drum, the loose end of which is attached to the device to be moved. In some instances this device is a small road scraper and by this means ore is transported short distances from the place where it is blasted down, and thence led into chutes to tram cars. One man controls the handle of the scraper and only one man is needed to operate the hoist. With some 10 signs of hoists, the throttle lever, when open, will stay in any position in which it may be when the hand is removed from it, and in most hoists, this throttle lever can be accidentally knocked into open position if it is hit by some external force. It will be understood, of course, that this frequently results in accident due to the hoist starting when men are in dangerous positions relative to the scraper or have their hands on a moving 15 part.

It is therefore an object of this invention to provide a locking handle for a throttle lever which cannot be accidentally moved to cause operation of said throttle lever.

Another object is to provide a throttle of such character that it will automatically return to inoperative position if the handle is released.

Still another object is to provide a simple, effective yet inexpensive locking and returning means for a throttle lever.

A further object is to provide a safety device which may be readily applied to existing machines as well as to machines initially provided with such device.

Other, various and more specific objects will readily occur from the specification, claims and drawings appended hereto.

In the drawings, wherein like reference characters are used to designate like parts—

Figure 1 is a side elevation of a winch or hoist having the safety handle applied thereto;

Figure 2 is an end elevation of the motor

housing of the winch, showing the safety handle in locked position; and

Figure 3 is an enlarged sectional view, showing the relation of the parts of the throttle handle, the handle being in locked 55 position.

A usual winch 10 of the tugger type is illustrated, being bolted or otherwise secured by bolts 32 to a base 11. This winch is provided with a drum 12 having the winding 60 rope 33 wrapped thereon, which drum is operated through the clutch mechanism 13 by a motor provided in the housing 15. Brake mechanism 14 is also provided for checking the movement of the drum. The throttle lever is indicated at 16 integral with or fastened to a pivotally mounted operating valve cylinder 17. The throttle valve handle comprises a member 18 fastened directly to the cylinder 17 and extending into the operating 65 handle 19. A shoulder 22 is provided on the end of the member 18 extending into the handle 19 and a spring 20 surrounds the member 18 and is disposed between the shoulder 22 and the apertured base 21 of the handle 70 75 and tends to force the shoulder 22 towards an end 34 of the handle. Or, in other words, tends to force the handle 19 towards a stationary locking member 25 provided on the housing 15. This handle is provided with a locking projection 23 extending through a guide 24 on the member 18, and in normal position cooperates with a hole or aperture 35 provided in the locking member 25. It will be seen that this member 25 is provided with 80 a base 26 which is fixed to the motor housing by any means, such as the bolts 31 which may also fasten the housing to the hoist. The member 25 is also provided with a cam portion 27 disposed in way of the path of rotation of the member 23. This cam portion may be provided with an attaching arm or lug 29 fastened to any upstanding member 30 of the motor housing by means of the bolt 28.

It will be understood that in normal position, that is, the locked position, the throttle lever is in the position indicated in Figure 2, that is, with the projection 23 extending into the aperture 35. In operating the motor, it is then necessary to pull the handle in a di- 95 100

rection away from the locking member 25. That will compress the spring 20 and remove member 23 from aperture 35, allowing the throttle lever to rotate the valve cylinder 17, 5 it being understood that the plunger 23 tends to move toward the cam 27 by the influence of the spring. If the throttle is in open position and the handle is released, the plunger 23 will be urged toward the cam 27 by the 10 spring 20 and the cam is so shaped that the spring will cause the plunger to travel along the cam face until it reaches the aperture 35 when it will enter said aperture and lock the throttle in inoperative position, cutting off 15 the power to the motor. Due to the lock, it will be seen that if the handle is accidentally struck, it cannot cause the motor to start as the throttle will not move due to the cooperation between member 23 and the aperture 35. 20 This member is then doubly safe as it cannot be accidentally operated, and if released while in operation, it will automatically seek an inoperative position.

It will be understood that this handle is 25 not only applicable to a hoist or winch as it may be applied to any other valve operating or throttle mechanism, and it will be seen that other and various forms of the device will occur to those skilled in the art so I do 30 not wish to be limited by the embodiment shown, which is only by way of illustration and not by way of limitation.

I claim:

1. In a device of the character described, 35 the combination of a fixed locking member, a pivoted control member normally locked in inoperative position, said member including a projection, a handle cooperating with and movable with respect to said projection and 40 having a locking member thereon cooperating with said fixed locking member, a cam leading to said fixed locking member and resilient means cooperating with the handle to urge the locking member along the cam surface 45 and into locking position.

2. In operating mechanism for hoists or the like the combination of a throttle including a plurality of relatively movable members, one of said members being a hand grip 50 and cooperating with said other member, a resilient member disposed between said members for urging said grip into a predetermined position, a projection disposed on said grip member, a cam member disposed adjacent said throttle and adapted to be contacted by said projection, a stop on said cam adapted to be contacted by said projection when said throttle is in predetermined position, said resilient member urging said projection toward said cam and causing said projection to be urged toward said stop.

3. In a device of the character described, 65 the combination of a fixed cam member, a rotary operating member, a projection thereon extending into an operating handle, a pro-

jection on said handle for locking said operating member in inoperative position, resilient means on said first mentioned projection for urging said second projection into locking position, said second projection co-operating with said fixed cam member when 70 said operating member is rotated to operative position to thereby tend to cause said operating member to move to inoperative position.

Signed at Virginia, Minnesota, this 18th 75 day of June, 1927.

RICHARD J. WILLIAMS.
